ATTORNEY

UNITED STATES PATENT OFFICE.

JOHN J. SULLIVAN, OF SPRINGFIELD, MASSACHUSETTS.

FOLDING TROUSERS CREASER AND STRETCHER.

Application filed October 1, 1921. Serial No. 504,796.

To all whom it may concern:

Be it known that JOHN J. SULLIVAN, citizen of the United States of America, residing at 169 Main St., Springfield, in the 5 county of Hampden and State of Massachusetts, has invented certain new and useful Improvements in Folding Trousers Creasers and Stretchers, of which the following is a specification.

- 10 This invention relates to trousers creasers and stretchers and its leading object is to provide an improved folding device for creasing and stretching trousers, which will maintain an upright position when inserted 15 in the leg of a trousers, and when desired may be folded upon itself so as to be capable of being inserted in a suit case or other small container, such as a steamer or other trunk.
- 20 Another object of the invention is the provision of a device of this character with a two piece frame, the terminals of which are hingedly connected to each other, so that the body of each section of the frame is 25 continuous, thus permitting more economical manufacture and easier assembling.

With the above and other objects in view the invention consists of certain new and useful constructions, arrangements and combinations, clearly described in the following specification and fully illustrated in the accompanying drawings, in which:—

Fig. 1 is a plan view.

Fig. 2 is a detail perspective view of a 35 hinge connection, showing the connected parts in partly folded position.

Fig. 3 is a side elevation thereof.

Fig. 4 is a detail plan view of the central 40 portion of the upper frame section with the name plate removed.

Fig. 5 is a detail plan view showing the 45 slideable coupling in its locked position.

Fig. 6 is a transverse sectional view 50 thereof.

55 Referring to the accompanying drawings illustrating the practical embodiment of my invention 5 designates the lower frame section and 6 the upper frame section, each of which is substantially W-shaped, thus having a central V-shaped portion or spring 7 and forming bars 8 and 9. The entire frame is made of wire having a beveled edge 10, and the forming bars comprising the divided sides of the frame carry this beveled edge 55 on their outer sides, so as to present to the

leg of the garment a narrow crease forming surface. A name plate 11 is folded over the central portion of the V-shaped spring 7 of the upper frame.

The terminals of each frame section are 60 located on opposite sides of the center of the frame. The terminals 5^a and 5^b of the side forming bars 8 and 9 of the lower frame section are disposed in abutting relation to the terminals 6^a and 6^b of the side 65 bars 8 and 9 of the upper frame 6, when the frame is in extended position, as shown in Fig. 1.

The two frame sections are held together by means of hinges 12 and 13. The hinge 70 12 is formed of two hinge members 12^a and 12^b, the former being welded or otherwise secured to the terminal 5^a of the side bar 8 and the latter being welded or otherwise secured to the terminal 6^a of the side bar 8. 75 The hinge members 12^a and 12^b are pivotally connected to each other by means of the pintle 12^c, extended through the hinge eyes 12^d and 12^e of the members 12^a and 12^b, respectively.

80 Each hinge is so designed that it will have a limited movement in the opening direction, and for this purpose the hinge members 12^a and 12^b are formed with shoulders or stops 12^f and 12^g, respectively, 85 which are adapted to abut against each when the frame sections are opened to the extended working or creasing position, as shown in Fig. 1.

80 The hinge members 12^a and 12^b are connected to the parts of the side bar 8 so that the pintle 12^c will be in registration with the joint formed by the abutting ends 5^a and 6^a of the side bar 8, and the flat end surfaces of the terminals 5^a and 6^a will provide shoulders or stops to limit the movement of the connected parts in an opening direction.

100 Each hinge member is secured to the inner side of its forming bar, so that the upper frame 6 will fold directly over the lower frame 5, with the beveled edges of the forming bars 8 and 9 maintained in the outer positions. The eyes of the hinge members are 105 preferably formed so as to be non-expansile, thus insuring that the two frame sections will not wobble on each other and will maintain a correct alignment. The ends of the pintles are headed to retain their positions. The hinge 13 is constructed in du- 110

plicate of the hinge 12, so that a detail description of the hinge member 13 is deemed unnecessary.

The arrangement of the hinges, each having a pair of abutting shoulders, on the confronting terminals of the side bars of the forming frames, provides a relatively wide surface to insure a positive holding of the frame sections in proper alignment in open position, while the heading of the pintles provides a safe friction joint between the parts of each frame. The hinges are located away from the beveled creasing edges, and the members of each hinge are preferably tapered outwardly so as to be devoid of any projecting surfaces.

My improved folding creaser and stretcher therefore includes companion forming frame sections, each formed of a single piece of wire, and the relatively movable sections of the side bars of the frame fold into extended opening position in correct alignment, so as to present a continuous forming edge on each side of the frame.

Figs. 5 and 6 show details of a sliding lock for holding the creaser and stretcher in open, extended position. This lock consists of a split tube 15 which is slidably mounted on the bars of the stretcher, and held against lateral displacement by means of inturned flanges 15^a and 15^b. The split tube 15 is adapted to bridge the gap of the abutting ends of the upper and lower sections so as to hold the side hinges extended away from each other.

Having described my invention I claim and desire to secure by Letters Patent:—

1. A creaser and stretcher for trousers composed of a pair of frame members, each frame member consisting of outer crease forming bars and a connecting spring adapted to maintain outward tension upon the said bars against the garment to be creased, the ends of the bars of one frame member being placed in contiguous relation to the ends of the bars of the other frame member, a hinge for connecting the adjacent ends of each pair of bars for folding movement, said hinge being secured against the inner sides of the engaged bars and the terminal portions of said bars forming stops to limit the movement of the frame members

upon each other in an opening direction, to maintain said frame members in substantially the same plane when in open position, the hinges being arranged to permit one frame member to fold upon the other frame member without separation thereof.

2. A folding trousers creaser and stretcher consisting of a pair of frame members, each frame member being formed of wire and having an outwardly projecting beveled edge, each frame member being of substantially W-shaped construction, the terminals of each frame member facing the terminals of the other frame member, a hinge connecting the adjacent side bars to each frame member, each hinge having a member having an offset eye, and an attaching portion, the attaching portion being supported directly at the inner side of one of the frame members and the eyes of each hinge being pivotally connected to each other, each hinge being also provided with a stop to hold the frame members in extended open position, the pivots being located in line with the joint between the terminals and said bars and in substantial axial alignment, whereby the frame members will fold on each other on a common axis.

3. A folding trousers creaser and stretcher consisting of a pair of frame members, each frame member being formed of wire and having an outwardly projecting bevelled edge, each frame member being of substantially W-shaped construction, the terminals of each frame member facing the terminals of the other frame member, a hinge connecting the adjacent side bars to each frame member, each hinge having a member having an offset eye, and an attaching portion, the attaching portion being supported directly at the inner side of one of the frame members and the eyes of each hinge being pivotally connected to each other, each hinge being also provided with a stop to hold the frame members in extended open position, the pivots being located in line with the joint between the terminals and said bars, and a sliding sleeve lock movable across each frame section to bridge the joint between the side bars and the frame section.

Signed by me at Springfield, Mass.
JOHN J. SULLIVAN.
